UNITED STATES PATENT OFFICE.

LAWRENCE E. JOHNSON, OF BOSTON, MASSACHUSETTS, ASSIGNOR TO ELLERY C. WRIGHT, OF BROCKTON, MASSACHUSETTS.

LAST.

1,181,969.

Specification of Letters Patent.

Patented May 2, 1916.

Application filed June 1, 1914. Serial No. 841,996.

To all whom it may concern:

Be it known that I, LAWRENCE E. JOHNSON, a citizen of the United States, and resident of Boston, county of Suffolk, State of Massachusetts, have invented an Improvement in Lasts, of which the following description, in connection with the accompanying drawings, is a specification, like letters on the drawings representing like parts.

My present invention is an improvement in hinged last construction, and has for its object to provide a very strong, simple, cheap and effective hinge and spring lock device with both the hinge and spring acting from the same pivotal position.

In the manufacture of hinged lasts it is customary to provide a spring between the forepart and the heel part, which is ordinarily fitted in special sockets provided therefor in both heel and forepart, to normally tend to force the two parts in extended position without any regard to the pivotal relation of the hinge uniting the forepart and heel part. By my present invention I have devised a hinged last with a spring member which is intended to normally force the last into its extended position, so as to act on the two parts of the last from the pivotal center on which said two parts are arranged to hinge, and in this manner I am enabled to secure a firm, even, and uniform bearing tension at all times upon the pivot or hinge connecting the forepart and heel part.

A further object of the present invention is to provide an automatic spring lock which will hold the forepart and heel part of a hinged last in their extended position and tend to hold or lock the same yieldingly in such position, requiring a very considerable effort at the initiation of the flexing or "breaking" movement to bend the last on its hinge, and which will, after the flexing is started, permit the further bending easily and without special resistance. This feature is of special importance, and I prefer to utilize one part of the novel form of spring which I have devised, to constitute the locking device and which will necessitate the extra effort at the initiation of the flexing or breaking of the last. I also prefer to have this locking device, which may be automatically thrown out by an extra effort, to be formed as a double metallic

bearing between the hinge member and the spring member.

Other features of the invention, novel combinations of parts and important advantages will be hereinafter pointed out and 60 claimed.

Referring to the drawings, illustrating a preferred embodiment of the invention, Figure 1 is a side view of my novel hinge last; Fig. 2 is a plan view, partly in section; 65 Fig. 3 is a cross sectional view of the hinge portion, with the last in extended position; and Fig. 4 is a cross sectional view, showing the last when flexed or broken.

I may apply my novel type of hinge and 70 spring member to any suitable style or form of two-part last, my improved last having the important feature of requiring but a minimum of cutting of the wood to fit both the hinge and spring members. Therefore 75 my present invention is peculiarly applicable to the type of lasts at present in general use, having a very high thin cone at the heel and an equally narrow crown in the forepart. In lasts of this type especially, it 80 is important that as little wood be removed to allow for the hinge and spring members, as is possible, in order to avoid the danger of weakening the last sections too greatly.

A forepart 1 and heel part 2 are shown, 85 with the line of cut 3 in a customary form, leaving the secant faces 4 and 5 on the forepart and heel part respectively to permit of the flexing of the last. A vertical kerf or saw cut is made in the forepart and the heel part at 6 and 7 respectively, to receive a vertical hinge member 8, which member extends into both the forepart and heel part, being preferably rigidly secured to the heel part by two pins 9 and 10, and 90 pivotally secured to the forepart by the pin 11. This construction permits the heel part and forepart to be swung relatively on the pin 11, the adjacent faces of each part on the line of cut 3 and the distance between the secant faces 4 and 5 permitting this swinging action, as clearly illustrated in Fig. 4. About the pin 11 I secure a spring 12, with a single turn around the pivot on either side of the hinged plate 8, one arm of the spring 13 being preferably positioned to bear against the heel part adjacent the plate 8, thence with a turn around the pivot pin 11 and a doubled portion 14 extending upwardly, over, and across 110

the hinge plate 8 to the pin on the other side of said plate, where a second turn is taken around the pin and the other end or arm 15 of the spring is left to bear against the 5 heel part in a similar position on the other side of the plate 8 to that of the first mentioned arm 13. In order to provide a proper seat for this spring 12 and for each of the arms thereof, I may recess the secant 10 faces 4 and 5 slightly, as indicated at 16 and 17 (see Figs. 2 and 3). I also prefer to provide a special bearing for the spring member on the forepart, as by looping the same, as illustrated at 18, thus giving a 15 double bearing at either side of the hinge plate 8, directly on the forepart at 19. These loops 18 and the free arms 13 and 15 will, of course, act to expand the two parts of the last into extended position, 20 with the pin 11 both as the fulcrum for the spring and as the pivotal point on which the two parts swing.

In order to provide the automatic locking feature for the last when in extended position, I prefer to curve the doubled part of the spring member 14 backwardly, as clearly shown in Figs. 1, 2, and 3, and to form on the plate 8 a recess 20 in such position that the rearwardly extended portion 14 of the 25 spring will act to catch therein, when the last is in extended position. The recess 20 is provided with a substantially vertical bearing face against which the doubled end 14 of the spring 12 is seated, in contact 30 therewith when the forepart and heel part are extended. This construction gives a spring locking device which tends to prevent the flexing of the last until a considerable effort is exerted thereon, and may constitute 35 as positive and rigid a lock as may be desired by increasing the strength of the spring. Preferably, however, the recess 20 is so formed that when a considerable "breaking" pressure is applied, the doubled 40 end 14 will snap upwardly over the edge of the recess and slide backwardly thereover, as illustrated in Fig. 4, permitting the rest of the flexing movement to be easily effected. It should be noted that the locking 45 part 14 of the spring has its own separate spring coils entirely independent of the coils of the spring 12 about the pivot 11. The latter exerts the expansible tension from the arms 13 and 15 on the heel part to 50 the faces 16 in the forepart, by the contact therewith of the loops 18. The locking part 14 of the spring gets its tension from the loops or coils 18 and from the position of the loops and the curve of the frame from 55 the loop to the recess 30 in the hinge plate. This construction gives such strength and pliability to a hinge last that the pivot pin 11 may be lowered considerably more than is now customary, without danger of the 60 last collapsing in use, and thus gain a 65

quicker "shortening" of the two parts when flexed on the hinge.

It will be readily appreciated that the construction herein described is very simple, cheap, and economical to manufacture, as 70 well as efficient in providing a combined spring and locking arrangement. Furthermore the important advantage of having a double spring effect in each arm of the spring gives long life to such spring, and 75 consequently to the last. A still further advantage is that, as illustrated in Fig. 4, when the last is flexed or broken, and the doubled end 14 of the spring slides along the top of the hinge plate 8, this top and 80 the spring are so formed as to frictionally hold the forepart and heel part of the last in flexed position.

Having described my invention, what I claim as new and desire to secure by Letters 85 Patent is:

1. A last having a forepart and a heel part hinged together, a hinge plate rigidly secured to one part and pivotally secured to the other part, and a spring member also 90 secured to the hinge pintle in the same pivotal position as the plate and coöperating with said plate to hold the last under a locking tension when in extended position and requiring a strong flexing movement to overcome the locking action at the initiation of 95 said flexing movement.

2. A last having a forepart and a heel part hinged together, a hinge plate rigidly secured to the heel part and a pivot pin for 100 securing it to the forepart, said hinge plate having a recess therein, and a spring coiled about said pivot pin and having a portion arranged for spring locking engagement with the recess in said hinge plate and having bearing portions on the wood of both 105 forepart and heel part at both sides of the hinge plate.

3. A last having a forepart and a heel part hinged together, a hinge plate rigidly 110 secured to the heel part and a pivot pin for securing it to the forepart, said hinge plate having a recess therein, and a spring coiled about said pivot pin to exert expansive action and having a doubled end portion arranged for yielding locking engagement with the recess in said hinge plate and having a separate tension coil to exert the locking tension.

4. A last having a forepart and a heel 120 part hinged together, a hinge plate rigidly secured to one part and a pivot pin for securing it to the other part, and a spring member to hold said last extended also secured in the same pivotal position as the 125 plate and having a portion independent of that part of the spring which acts to expand the last and coöperating with said plate to hold the last yieldingly locked when in extended position and requiring a strong flex- 130

ing movement to overcome said locking action at the initiation of said flexing movement.

5. A last having a forepart and a heel part hinged together, a vertical hinge plate rigidly secured to the heel part and a pivot pin for securing it to the forepart, said hinge plate having a locking recess in its uppermost portion, a spring coiled about 5 said pivot pin and having a doubled end portion arranged adjacent the recess in said hinge plate and having bearing portions on the wood of both forepart and heel part at both sides of the hinge plate, said spring 10 having its doubled portion curved backwardly to effect a substantial locking engagement with the recess in the hinge plate when the last is in extended position.
6. A last having a forepart and a heel part hinged together, a vertical hinge plate rigidly secured to the heel part and a pivot pin for securing it to the forepart, said hinge plate having a locking recess in its uppermost portion, a spring coiled about said 15 pivot pin to exert expansive action on the last parts, and having an extension arranged adjacent the recess in said hinge plate and a separate spring coil for said extension, said extension being curved backwardly to effect a substantial locking engagement with the recess in the hinge plate when the last is in extended position.

7. A last having a forepart and a heel part hinged together, a hinge plate rigidly secured to the heel part and pivotally secured to the forepart, said hinge plate having a recess therein, and a spring coiled about said pivot pin to exert expansive action and having a doubled end portion arranged for yielding locking engagement with the recess in said hinge plate and having a separate tension coil to exert the locking tension, said separate tension coil having a bearing on the wood of the forepart 40 between the pivot pin and said recess.

8. A last having a forepart and a heel part hinged together, a hinge plate rigidly secured to the heel part and pivotally secured to the forepart, said hinge plate having a recess therein, and a spring coiled 45

about said pivot pin to exert expansive action and having a doubled end portion arranged for yielding locking engagement with the recess in said hinge plate and having a separate tension coil to exert the locking tension, said separate tension coil having a bearing on the wood of the forepart above the pivot pin and approximately opposite the recess in said hinge plate.

9. A last having a forepart and a heel part hinged together, a vertical hinge plate rigidly secured to the heel part and pivotally secured to the forepart, said hinge plate having a locking recess in its uppermost portion, and a spring coiled about 60 said pivot pin and having a doubled end portion arranged adjacent the recess in said hinge plate and having bearing portions on the wood of both forepart and heel part at both sides of the hinge plate, said spring 65 having its doubled portion curved backwardly to effect a substantial locking engagement with the recess in the hinge plate when the last is in extended position, the recess engaging doubled end portion of said 70 spring coils at its bearing portions on the wood each side of the hinge plate.

10. A last having a forepart and a heel part hinged together, a hinge plate rigidly secured to the heel part and pivotally secured 80 to the forepart, said hinge plate having a recess therein, and a spring coiled about said pivot pin and having a portion arranged for spring locking engagement with the recess in said hinge plate and having bearing portions on the wood of both forepart and heel part at both sides of the hinge plate, said bearing portions constituting expansible 85 means to hold the last parts in expanded position, said spring having separate spring 90 coiled portions to give independent spring tension on said locking portion of the spring.

In testimony whereof, I have signed my name to this specification, in the presence of two subscribing witnesses.
